UNITED STATES PATENT OFFICE.

JAMES H. SCOTT, OF LOS ANGELES, CALIFORNIA, ASSIGNOR OF ONE-HALF TO NORA E. JEWETT, OF LOS ANGELES, CALIFORNIA.

PERAMBULATOR AND CRADLE.

1,297,018.

Specification of Letters Patent. Patented Mar. 11, 1919.

Application filed April 4, 1918. Serial No. 226,771.

To all whom it may concern:

Be it known that I, JAMES H. SCOTT, a citizen of the United States, residing at Los Angeles, county of Los Angeles, and State 5 of California, have invented a certain new and useful Improvement in Perambulators and Cradles, of which the following is a specification.

My invention relates to a device for supporting a child while learning to walk and it has especial reference to a perambulator adapted for stationary erection in a nursery or other place, objects of the invention being to provide a light, strong and durable arrangement which may be quickly set up and dismantled, and in which the weight of the child is resiliently carried during its ambulatory traverse, whereby the sudden seating of the child in the carriage of the device, due 10 to its weak limbs, is accompanied by no shock or jar thus encouraging the child to further exertion in learning to gain the full use of its limbs.

Further objects of the invention are to 25 provide a comfortable device for instructing children to walk and at the same time affording them enjoyment and beneficial exercise, to provide a device in which the carriage may serve as a cradle or as a support for a 30 cradle, and in which the carriage may be adjusted relatively to surface above which it is suspended.

My invention is also applicable and useful 35 in surgical wards and hospitals for enabling children and others to engage in exercise and practice for regaining natural motions lost temporarily by reason of injury or operation.

Other objects will appear from the subjoined specification in connection with the 40 accompanying drawing, representing a preferred embodiment of the invention.

In the drawing,

Figure 1 is a side elevation, partly in section showing my invention used either as an 45 ambulator or a cradle.

Fig. 2 is a fragmentary plan view showing the saddle for the person to be carried therein.

Fig. 3 is a plan view of the plate for supporting the upper end of the standard, and

Fig. 4 is a side view of a modified form.

My invention comprises in general a carrier attached to a standard and rotatable in a circular plane, and specifically my invention consists of a vertical standard 1,

loosely mounted in a cup or bearing 2 in a suitable base 3, which may be temporarily or permanently fastened to the floor or ground. The upper end of said standard is provided with a collar 4 for supporting 60 a disk 5, which is arranged to fit over the upper end of the standard. This disk is provided with a plurality of holes 6 in which may be secured a plurality of guy wires or ropes 7 for maintaining the standard in a 65 steady upright position.

Adjustable on the standard 1 is a clamp 8 adapted to be tightened thereon in adjusted position by any suitable means as a thumb screw 9, which constitutes a pivotal support 70 for a normally horizontal rod or bar 10, the end of which is formed in an annulus or hoop 11. Attached to the hoop or annulus 11, is a saddle or carrier 12, disposed at such a height from the floor or ground that comfortable walking contact therewith may be had by the child or other person occupying the same, this height obviously being regulable by the clamp 8 and by other means presently appearing.

The hooped end of the horizontal bar 10 may be used for supporting a cradle or may be so formed that it itself constitutes a 80 cradle.

The horizontal bar 10 is yieldingly supported from the vertical standard 1, by the following means, consisting of preferably a tubular member 13, pivotally connected to an adjustable clamp 14, by a thumb screw 15, or other means, which is arranged to 90 tighten the clamp 14 on the horizontal bar and on the end of the tubular member 13, which, as seen, extends outwardly at an angle to the vertical plane of the standard and is provided with a removable apertured cap 95 16.

Operable within said tubular member and relatively thereto is a rod 17, having a head 18, and a spring coiled thereabout. This rod 17, is pivotally connected to a pin or other means 20 which serves to secure 100 an adjustable clamp 21, on the standard 1. By this means, the weight of the child or other person is resiliently supported during the circulatory ambulation, and the adjustability of the clamps provides for ready accommodation to different heights and condition, whereby the sitting posture of the person may be as nearly parallel with the floor as practicable.

Fig. 4 illustrates a slightly different form 110

of structure. It comprises a post or short stationary standard 22, rigidly secured in any suitable manner to a base 23. On the standard 22 is loosely fitted a sleeve 24 which surrounds the standard and is adapted to be clamped on the end of a horizontal bar 26 by a pin or set screw 25, which also forms a pivot for said bar. A spring 27 is coiled about said standard and exerts tension on said sleeve 24 to hold the bar 26 in normally horizontal position. A cap 28, on said standard may serve for adjusting the tension of said spring.

The horizontal bar 26 is offset as seen, and the end thereof formed in a loop or hoop 29, for a saddle 30 or other contrivance for supporting a child or other person, the loop or hoop lying in the same, but on a higher, parallel plane than the portion connected with the standard, thereby providing the height required by the user.

On the horizontal bar 26, is a roller or other rotatable element 31, constituting a fulcrum for the bar 26, which, when the saddle is occupied, is yieldingly resisted by the spring 27.

The ambulation of the patient in this instance occurs relatively to the fixed stand-

ard, but in the former case, the entire structure rotates.

30

What I claim, is:—

1. A perambulator comprising a base, a standard rigidly secured in said base, a sleeve surrounding said standard, a horizontal off-set bar attached to said sleeve and 35 its end formed in a loop, a fulcrum roller intermediate said horizontal bar, and a yielding means on said standard exerting tension on said sleeve.

2. A perambulator comprising a base, a 40 vertical standard rigidly secured in said base, a horizontal bar rotatably attached to said standard and having an off-set portion the end of which is formed in a loop, a carrier in said loop, a fulcrum wheel intermediate said horizontal bar, a spring on said standard exerting tension against said horizontal bar and means for adjusting the tension of said spring.

45

In testimony whereof I have set my hand 50 in the presence of two witnesses.

JAMES H. SCOTT.
